Assoc'd to

Orth, Chase, and North, of Philadelphia, Penn.

Letters Patent No. 1794, dated June 30. 1803.

The schedule referred to in these Letters Patent and making part of the same.

To all whom it may concern:

Be it known that we Garrison Smith, and Henry Brown, of the firm of Smith and Brown, of the City of Philadelphia, in the State of Pennsylvania, have invented or produced a new and original ornamental Design for the Plates of a wood stove; and we do hereby declare that the following is a full and exact description of the same, reference being had to the accompanying drawings, making a part of this specification, in which figure 1, is the front end plate of the stove; figure 2, the back end plate; figure 3, one of the like side plates; and figure 4, one of the like doors of the said side plates.

The front plate (figure 1) has a raised and depressed ornamental figure in the centre of its face; and the back plate (figure 2,) has a double figure of the same raised and depressed character, in the central portion of its face whilst both of the said plates have a bas relief column, along each of their side edges, ornamented by a series of raised configurations a, a, as shown in that arrangement, and the said front, and back, plates have each a raised moulding b. b. across its upper end whose transverse section is represented by the dotted line 1.

The side plates (figure 3) are each bounded by a raised moulding c. c. whose transverse section is represented by the dotted line 2; and has also a raised and depressed ornamental configuration in the centre of its lower face.

The side doors (figure 4.) of the said side plates, have each a raised and depressed configuration in the centre of its face, and is bounded by a raised moulding d. d. whose transverse section is indicated by the dotted line 3.

What we claim as our invention or production, and desire to secure by letters patent is a design for the plates of a wood stove as shown and described.
